METHOD OF AND APPARATUS FOR WASHING BOTTLES

Filed Aug. 6, 1923

2 Sheets-Sheet 2

Charles W. Hottmann, INVENTOR,
BY
Hedderlein & Reinhardt, ATTORNEYS.

UNITED STATES PATENT OFFICE.

CHARLES W. HOTTMANN, OF PHILADELPHIA, PENNSYLVANIA.

METHOD OF AND APPARATUS FOR WASHING BOTTLES.

Application filed August 6, 1923. Serial No. 655,801.

To all whom it may concern:

Be it known that I, CHARLES W. HOTTMANN, a citizen of the United States, residing in the city and county of Philadelphia and State of Pennsylvania, have invented a new and useful Method of and Apparatus for Washing Bottles, of which the following is a specification.

My invention relates in general to a class 10 of devices employed for the cleansing or cleaning-out of the interiors of bottles, jars, vessels and other liquid containers, from the insides of which it is desired to remove all traces or remainders of the contents 15 after the bottles or containers have been emptied.

My invention further relates to the use for the purposes of such cleansing both of shot and of a fluid, such as for example, 20 water; and its principal object is the construction of a washing apparatus to which an emptied, but internally dirty, bottle or other vessel is applied, and into the mouth, spout or discharging opening of which shot 25 is introduced under the high pressure of a spout or column of injected fluid, preferably water, which occasions not only the introduction of the desired quantity of shot through the mouth into the hollow interior of the 30 bottle or other vessel, but also its circulation within and throughout said interior, so that by the well known action of the shot the entire interior is both rapidly and thoroughly 35 cleansed,—the shot, for further use, being returned to its original holder and the dirty water permitted to escape.

My invention further comprehends a novel method of effecting the circulation of the shot. 40 A further and important object of my invention is the construction of an inexpensive and simple device particularly adapted, for instance, for household use, which can be placed near a sink, a water faucet of which 45 can be utilized for the water supply and the sink itself for the water discharge.

A further object in the same connection is that the device should be small and of compact construction so that it can be easily 50 carried and easily moved from place to place, and which is adapted either to be stood upon a level surface such as a table or a drain board, or, if desired, to be attached to a wall or other upright surface.

I do not, however, of course, confine myself to the use of a single washing device

but contemplate the assemblage of my bottle washers in any desired plurality and arrangement, so that a large number of bottles can simultaneously be washed. 60

With the foregoing, and other, objects in view, my invention comprehends a bottle washing device of the character hereinafter described and claimed.

For the purpose of illustrating my invention I have shown in the accompanying drawings a certain type and embodiment of it which is at present preferred by me because in practice it has given satisfactory and reliable results. It is to be understood, 70 however, that the various instrumentalities in which my invention is shown as embodied can be variously arranged and organized, and that my invention is not therefore limited to the precise arrangement and organization 75 of the instrumentalities shown in the drawings and hereinafter described.

In the drawings, Figure 1 represents a side elevational view of a bottle washing apparatus embodying my invention. 80

Figure 2 represents the apparatus of Figure 1 centrally and vertically sectioned throughout, illustrating also a fragmentary and partially sectional view of a bottle in place in the washer. 85

Figure 3 represents a plan of my washer, the bottle not having been introduced.

Figure 4 represents a section on the line 4—4 of Figure 2.

Figure 5 represents a perspective of the 90 basket removed from the machine.

Figure 6 represents a side elevation of the secondary injector removed from the machine.

Figure 7 represents a fragmentary view 95 of a part of the shot container removed from the machine.

Figure 8 represents a section on the line 8—8 of Figure 2.

Figure 9 represents a section on the line 100 9—9 of Figure 1.

Similar numerals of reference indicate corresponding parts.

In the drawings, 1 designates the base of my washer, of any preferred form and construction, upon which the machine itself 105 rests.

Erected from this base is a supporting standard 2, the hollow interior 3 of which at its upper part is formed into or provided 110 with a primary injecting nozzle or injector 4, below which and, in the construction

shown, about midway of the length of the standard, is a valve seat 5 which is adapted to be closed by a valve 6 at the upper end of a valve rod 7 which extends downwardly through a gasket 8 to a pivotal connection at 9 with the inner end of a lever 10 fulcrumed at 11 to the base 1 and at its outer end pivoted at 12 to an operating rod 13 hereinafter described.

Below the valve 6 a water supply connection in the form of a nipple 14 extends laterally from the hollow interior of the standard to a connection, conveniently being a water tube 15, with a faucet or other source of water supply.

Surrounding the exterior of the supporting standard 2 is a fixed sleeve 16 which at its upper end is formed into or connected with the basal portion of a preferably conical hopper 17 for containing the shot 18 which I use.

19 designates what I call a casing or basket-container in the form of an open-topped cylinder, within which is contained a basket 20, being a cylindric body formed of wire gauze or equivalent foraminous material and open at both top and bottom.

The basket 20 is centered within its container 19 preferably by peripheral beads 21 and 22 of which 21 bears against the inner walls of the container and 22 rests against the upper inner rim of the hopper on the line of its circular bend with regard to the container.

23 designates a diaphragm fixedly secured within the basket near its lower open end. This diaphragm serves as the article support upon which is adapted to rest the mouth 24 of a bottle or other container 25, and for convenience in centering the bottle in its introduction into the basket I surround a central opening 26 in the diaphragm with a circular slope 27 as best seen in Figure 2.

Encompassing the nozzle of the primary injector 4 is what I call an injecting chamber 28, formed by conical extension 30 of a rotatable sleeve 29 which fits concentrically around and is rotatable within the outer fixed sleeve 16, as seen in Figures 2, 6, 8, and 9,—the said conical extension 30 being continued upward through the basket 20 to form what I call a secondary injector 31 which extends sufficiently beyond the basket to be entered within the neck of a bottle so as to terminate about within the bottle throat 32, as clearly seen in Figure 2.

In order to make possible the rotary movement of the sleeve 29 to a given distance within the fixed sleeve, see Figures 6 and 7, I use a thumb-piece 34 being a rod fixed to and extending radially outward from the movable sleeve 29 through a slot 33 in the fixed sleeve, as seen in Figure 1.

The purpose of rotating the movable sleeve 29 with reference to the fixed sleeve

16 is to cause the closing or opening of shot-openings 35 in the fixed sleeve, see Figure 7, by the rotary movement of segmental webs 36 formed between the conical extension 30 and the movable sleeve 29 which are formed between shot openings 37 in the movable sleeve, as seen in separated relationship in Figures 6 and 7, and in closed relationship in Figure 8.

Obviously, when the shot openings 35 and 37 register, the shot in the hopper 17 will fall into the basal portion of the injecting chamber 28 and be subject to the suction of the water stream passing through the primary injector 4 and upwardly into the secondary injector 31.

The operation of my machine is due primarily to the control of the valve 6 with relation to its seat 5, and this control is effected by the operation of a lever 38 the inner part of which is located in the hopper, the fulcrum 39 of which is attached to the basket container 19, and the extension 40 of which outside of the hopper is connected through the operating rod 13 with the lower lever 10 already described. Thus, in the operating position illustrated in Figure 2, the water valve 6 has been opened by the pressure of the mouth of the bottle when the bottle has been introduced between the bottle supporting arms 41 upon the lever 38 so as to deflect it from the position shown in dotted lines in Figure 2 into that shown in full lines in said figure.

42 designates a plurality of water outlets 100 through the side walls of the basket-container, which in conjunction, if desired, with lateral openings 43 in the diaphragm, see Figure 3, serve to permit of the discharge of the water after it has performed its office 105 of cleansing and scouring a particular bottle.

In the description of the construction of the apparatus, the operation and function of the several parts has been so clearly described that a further description of the operation as such is, as I think, unnecessary.

I may add, however, that whatever be the character of the bottle, jar, or other hollow article to be cleaned, it will be apparent that when it has been introduced into the basket, its action upon the then closed water valve, through the connecting lever devices will cause the opening of the valve and permit of the inrush of the water through the injectors and the utilization of its inducting action to effect such a circulation in the injecting chamber as will draw the shot into said chamber and cause such a circulation throughout the hollow interior of the article to be cleansed as by the scouring action will occasion the very rapid cleansing of the entire interior of the article to be cleansed.

The withdrawal of the article after the cleansing operation has been completed, will effect the release of the upper lever and

through the lever connection the closure of the valve to stop the supply of fluid and permit of the gravitational return of the shot through the opening in the diaphragm into the shot hopper, the dirty water discharging itself through the water outlets and openings of the container.

In operating the device it is, of course, necessary, before inserting the bottle, to cause the registry of the shot openings 35 and 37 by the thumb-piece 34, so that the shot will be free to return into the bottom of the injecting chamber 28.

It is possible to operate the machine without opening and closing the shot openings, but it is of advantage that they be opened or closed. For example, in some cases it is desirable to rinse the bottles, in which case the openings through which the shot passes may be closed.

It will now be apparent that I have devised a novel and useful bottle cleaner which embodies the features of advantage enumerated as desirable in the statement of the invention and the above description, and while I have, in the present instance, shown and described a preferred embodiment thereof which will give in practice satisfactory and reliable results, it is to be understood that such embodiment is susceptible of modification in various particulars without departing from the spirit or scope of the invention or sacrificing any of its advantages.

Having thus described my invention what I claim and desire to secure by Letters Patent is:

1. In a bottle washing machine, a base

provided with a vertical, hollow standard which standard has a restricted passage forming a nozzle, a casing forming a shot receiving chamber, a basket within said casing which casing is carried by said standard, a control valve for said restricted passage, a lower lever fulcrumed to said base one end of which lever is connected with said valve, a rod connected to the other end of said lever, an upper lever fulcrumed to said casing and having one end projected thereto and the other end connected to said rod, the free end of said upper lever normally being adapted to be tripped by a bottle neck and means carried within said basket to support the neck of a bottle.

2. In a bottle washing machine, a base provided with a vertical, hollow standard which standard has a restricted passage forming a nozzle, a casing forming a shot receiving chamber, a foraminous basket within said casing which casing is carried by said standard, a control valve for said restricted passage, a lower lever fulcrumed to said base one end of which lever is connected with said valve, a rod connected to the other end of said lever, an upper lever fulcrumed to said casing and having one end projected thereto and the other end connected to said rod, the free end of said upper lever normally being in substantially horizontal position above said foraminous basket and adapted to be tripped by a bottle neck, and means carried within said foraminous basket to support the neck of a bottle.

CHARLES W. HOTTMANN.
